LABORATORY TABLE UNIT FOR GROUP
INSTRUCTION

Clive Nall, 415 Spruce St., Redwood City, Calif.

Filed Nov. 4, 1963, Ser. No. 77,261

Term of patent 14 years

(Cl. D16—2)

FIGURE 1 is a perspective view of a laboratory table unit for group instruction, showing my new design; and FIGURE 2 is a top plan view thereof.

The dominant features of the design reside in the portions shown in full lines on the drawing.

I claim:

The ornamental design for a laboratory table unit for group instruction, substantially as shown and described.
